UNITED STATES PATENT OFFICE.

NICHOLAS U. LUDWIG, OF BUFFALO, NEW YORK, ASSIGNOR OF ONE-THIRD TO
GEORGE W. WEYAND, OF BUFFALO, NEW YORK.

COMBINED BRICK KILN AND DRIER.

Application filed May 20, 1922. Serial No. 562,419.

To all whom it may concern:

Be it known that I, NICHOLAS U. LUDWIG, a citizen of the United States, and a resident of Buffalo, in the county of Erie and State of New York, have invented certain new and useful Improvements in Combined Brick Kilns and Driers, of which the following is a specification.

This invention relates to the general 10 class of plastic and earthenware apparatus, and more particularly to kilns employed for drying and burning materials that are presented to zones of the apparatus while traveling horizontally, the said invention 15 being classed as a kiln for horizontally traveling material.

It is an object of this invention to produce a kiln of the tunnel type, associated 20 with novel means for heating the tunnel in an intermediate zone to a degree which will result in burning bricks or the like, and the zone just mentioned might be regarded as the furnace or firing zone.

It is an object of the invention to provide 25 a plurality of firing cavities where burners for liquid or gaseous fuel are stationed, associated with means for supplying the fuel to the burners, and the provision of an open wall thereabove preferably formed by superimposed layers of 30 bricks arranged to produce an open-work structure through which the products of combustion from the burners may circulate and from which they will find their 35 way to the tunnel, it being understood that the said tunnel is elongated on each side of the firing zone, in order that bricks on carriers, or the material to be burned or treated will be gradually heated on approaching the firing zone and will gradually cool as in passing from the firing zone to the tunnel exit.

It is a further object of this invention 45 to produce a tunnel of the character indicated, having a plurality of baffle walls in spaced relation to one another, the openings between the edges of the baffles being restricted as compared with the space enclosed by the tunnel walls at the sides of 50 the said baffles, and it is the purpose of the inventor that carriers or cars shall have the bricks to be burned arranged in

courses thereon, in the general configuration of the edges of the baffles, and so arranged that only a small space or clearance 55 exists between the ends and top of the courses and the edges of the baffles, in order that the circulation of the heated air may be restricted, due to the very small space or clearance afforded for its passage past the surfaces of the bricks.

It is furthermore an object of this invention to provide novel means for delivering the cars containing the bricks to the tunnel in a manner to prevent radiation or 65 escape of the heat contained in the tunnel, a condition which results in economy in the operation of the kiln.

It is a further object of this invention to produce cars adapted to run on suitable 70 tracks within the tunnel, the said cars having longitudinally extending troughs at their sides adapted to contain a refractory sealing agent in which a rib, fin or the like, forming a stationary part of the tunnel, 75 extends to guard against the escape of heat and to prevent the bottom of the tunnel from becoming fouled through the deposit of sand or the like.

It is a still further object of this invention to provide a tunnel or housing for 80 drying bricks prior to their being delivered to the kiln tunnel, and the provision of novel means for conserving the partially spent heat from the kiln for use in the 85 drier, means being provided for conducting or conveying the heat from the kiln to the end of the drier remote from the end in which the green or wet bricks are introduced into the drier, the said drier being 90 provided with a novel conveyer on which the bricks are deposited and by which they are carried through the drier channel.

It is a further object of this invention to produce a kiln of the character indicated, and a drier in associated relation to each other and to a stack to which heat may pass from the drier or from the kiln, means being also provided for diverting the heat from the kiln to the drier, or to 100 the stack, according to the degree of heat emanating from the kiln, and the degree of heat desired for use in the drier.

It is a further object of this invention

to produce an apparatus of the character indicated in which the cars have interlocking or interengaging joints at their ends which serve to prevent the circulation of air and the escape of heat from the zone of the kiln tunnel in which the bricks are stored or being transferred while they are burned.

It is a further object of this invention 10 to produce an apparatus of the character indicated which will possess advantages in points of efficiency and simplicity, the same being comparatively inexpensive to produce.

15 With the foregoing and other objects in view, the invention consists in the details of construction, and in the arrangement and combination of parts to be hereinafter more fully set forth and claimed.

20 In describing the invention in detail, reference will be had to the accompanying drawings forming part of this application wherein like characters denote corresponding parts in the several views, and in 25 which—

Figure 1 illustrates a horizontal sectional view of the combined kiln and drier and the circulating flues associated therewith;

Figure 2 illustrates a sectional view 30 through the firing zone of the burner on a line corresponding with the line 2—2 of Fig. 1;

Figure 3 illustrates a sectional view on a line corresponding with the line 3—3 of 35 Fig. 1;

Figure 4 illustrates a longitudinal sectional view of a fragment of the firing zone and a fragment of the adjacent portion of the tunnel;

40 Figure 5 illustrates a longitudinal sectional view of a fragment of the drier;

Figure 6 illustrates a transverse sectional view of the drier; and

45 Figure 7 illustrates an enlarged detail sectional view showing the joint between a car and a tunnel wall.

In these drawings 10 denotes the firing zone of the tunnel structure, 11 the zone of approach to the firing zone, and 12 the zone 50 of discharge from the firing zone, it being understood that the zone of approach is relatively longer than the zone of discharge or exit, and that this relation is maintained for the purpose of gradually heating the 55 bricks as they approach the firing zone and to gradually cool them after leaving the firing zone, although the length of time required for cooling is proportionately less than that required for the gradual heating of the 60 bricks.

A trap-like entrance area 14 constitutes an extension of the zone 11 and there is a door 15 which guards the mouth of the tunnel 65 so that cars loaded with bricks may be delivered to the entrance area without permit-

ting the escape of heat from the kiln. The entrance area also is guarded by an outer door 16, and when the car or cars have been delivered to the entrance area and the door 16 is closed, the door 15 may be opened to 70 permit the car to pass into the kiln, and thereafter, the door 15 will again be closed so that the operation may be repeated without undue loss of heat.

An exit area 17 is of the same general 75 construction as the entrance area, and the relation of parts as to the doors and the like is the same, and the purposes are, of course, the same.

The firing or burning zone is slightly 80 larger in cross sectional area than the zone of approach or the zone of exit, and each side of the tunnel is provided with a plurality of furnaces or heating chambers 18 separated from each other by walls or partitions such as 19. The pits or fire boxes 20 may contain suitable liquid or gaseous fuel burners, and each heating chamber preferably contains superimposed checkered bricks shown at 21 to permit the products of combustion to circulate and escape from the inner sides of the furnaces to the tunnel. Appropriate means may be provided for supplying fuel and for controlling the burners, but, these features do not form parts 90 of the present invention, and as one skilled in the art will understand the construction and operation of these features, a detailed description or showing thereof is believed unnecessary.

The tunnel wall at each end of the firing or burning zone is preferably thick as compared with the outer end of the zone of approach, in order to prevent radiation of the heat, and the inner walls of the tunnel 105 from the firing zone to the entrance area are provided with baffle arches 22 which are spaced apart from each other, the distance between the said baffle arches being increased as the outer end of the zone of approach is reached. It is the purpose of 110 the inventor that these baffle arches shall be approximately five feet apart in the firing zone and that the distance between them shall increase to eight or ten feet or even 115 more, under some conditions, toward the outer end of the zone of approach. As shown in the drawing, and particularly Fig. 3, the inner edges of the baffle arches are angularly disposed with relation to each 120 other, in order that the courses of bricks carried on the trucks or cars, to be presently explained, may have their ends terminate so that they will be in close proximity to the inner edges of the baffle arches to produce restricted openings between the ends of 125 the courses and the said arches and between the top course of bricks and the top wall of the said arches.

The bottom of the tunnel may be provided 130

with any suitable track 23 on which the cars 24 may travel, the bottom 25 of each car having its edges flanged as shown at 26 to fit into grooves 27 formed longitudinally 5 of the side walls 28 and 29 of the tunnel. The purpose of this close fitting relation of the car and tunnel lining or tunnel wall is to prevent the circulation of the heated air downwardly, and this arrangement therefore 10 confines the heat to that area of the tunnel occupied by the material to be burned.

As a further means for effectually sealing the upper area of the tunnel from the 15 lower area thereof, depending flanges 30 are formed integral with a lining plate 31 secured in a recess 32 in each side wall of the tunnel, and the beams 33 that are employed for supporting the bottom of the 20 car, or at least the beams at each side of the car bottom, have troughs 34 secured on them, and the outer flange or side 35 of each trough extends upwardly above the plane of the lower edge of the flange 30. Each 25 trough is supplied with a sealing agent 36 preferably of refractory material such as sand, and therefore, a sealed joint is formed by the flange which extends into the sand so that heat cannot radiate to the bottom 30 of the tunnel and affect the running gear of the cars.

The car bottoms have their ends provided with flanges 37 in such relation to one another that they practically interlock to 35 form a joint which will tend to retard the circulation of heat between the ends of the cars, a condition which is intended to further prevent the escape of heat from the area occupied by the material to be treated.

40 The system is provided with a stack 38 which is in communication with one end of the tunnel by any suitable duct 39, which may be provided with an appropriate damper for controlling the circulation of the 45 heated air to the stack.

The duct or underground flue 40 is in communication with the stack and with the tunnel through the medium of an outlet box 41, provided with a damper, conventionally 50 shown at 42, and the said outlet box 41 is also in communication with a duct or flue 43 which discharges into a drying tunnel 44. The drying tunnel preferably extends parallel with the kiln in spaced relation 55 thereto, and the heat from the kiln may be discharged partially or wholly into the drying tunnel, according to the degree of heat emanating from the kiln.

60 The drying tunnel, which is shown in cross section in Fig. 6, may have a suitable conveyer 45, the brick supporting element 46 of which extends over ledges 47 and 48 on the inner surfaces of the side walls to produce an overlapping joint that will prevent the escape of heat from above the con-

veyer, and the conveyer may be operated in any appropriate way to carry bricks from the end of the conveyer adjacent the stack 38 to the end of the conveyer which is in proximity to the entrance area of the tunnel. 70

As heat is delivered to the drier at the end remote from the point where bricks enter the drier, it will be observed that the heat circulates by passing rearwardly in the 75 drier and that the bricks being conveyed in the drier are subjected to heat of higher temperature as they are advanced in the drier, a condition which results in an efficient and satisfactory treatment. 80

Should the heat emanating from the kiln be greater than that desired for imparting proper temperature to the drier, it may be permitted to find its way directly to the stack through the flue 40, or the valves or dampers may be so operated as to direct all 85 of the heat to the drier.

In forming the fire chambers by the interposition of the dividing walls 19, every other wall may be provided with a manhole 90 49, and thus the number of manholes and covers for permitting access to the interior may be reduced. This construction will be more desirable perhaps than where a manhole is provided for each furnace section, as 95 it would minimize the joints or door openings which might permit the escape of heat.

The checkered superimposed bricks have their courses so arranged that they recede 100 step by step from the inner wall of the tunnel, and the flues or passages formed by the superimposed bricks are of gradually increased height from the inner wall of the tunnel to the outer wall of the furnace to convey the heat to different heights in the 105 tunnel.

It will be seen from an inspection of the drawing that the baffle arches are of a contour that their edges are unbroken, except at the angularly disposed portions thereof, 110 and this arrangement permits the piling of material on the car with its outer surfaces conforming to the contours of the arches, and it is the purpose of the inventor that the material shall be so placed as to leave 115 very restricted openings or clearances between the piles of material and the edges of the arches. This will serve to prevent the circulation of heat, to an undue extent, from the chamber between two arches to a chamber 120 between other arches, and it will serve to permit the firing of the kiln in zones having different temperatures in order that the material entering the kiln may be progressively heated, and in order too that as 125 it is advancing to the exit of the kiln, it will be progressively cooled.

The arrangement of the sealing trough under the car also serves to increase the capacity of the firing zone of the kiln, as 130

compared with any devices that have the sealing trough above the body of the car.

I claim:

In a kiln for burning bricks, a tunnel, firing chambers on each side of the tunnel, superimposed checkered bricks in each chamber, the inner edges of the courses of the

bricks being stepped outwardly toward the top, the flues formed by the checkered arrangement of the bricks being gradually higher from the inner edge to the outer wall of the said chamber, and means for generating heat under the checkered structure. 10

NICHOLAS U. LUDWIG.
